[57] CLAIM

The ornamental design for a shield and attractant for a
hummingbird feeder, as shown and described.

DESCRIPTION

FIG. 1 is a perspective view of a shield and attractant
for a hummingbird feeder showing my new design, the
broken-line showing of the feeder mechanism being for
illustrative purposes only and forming no part of the
claimed design;

FIG. 2 is a front elevation thereof;

FIG. 3 is a left side elevation thereof;

FIG. 4 is a top plan view thereof, the bottom being
identical in appearance;

FIG. 5 is a rear elevation thereof; and

FIG. 6 is a right side elevation thereof.

FIG. 1.

FIG. 4.

FIG. 2.

4

FIG. 3.

FIG. 5.

FIG. 6.
